BLUEPRINT APPARATUS AND METHOD

Frederick H. Crofoot, Chicago, and Edward G. Crofoot, Park Ridge, Ill.

Application April 7, 1938, Serial No. 200,660

17 Claims. (CL 95—75)

This invention relates to improvements in blueprint machines and processes.

An object of the invention is to provide means in a blueprint machine and steps in an improved process for applying an intensifying solution to a print such as the intensifying solution taught in the patent to Kwech, No. 1,877,246. With this object in mind, we have provided a highly improved blueprint machine and devised an improved method for applying intensifying or other solution to the print after exposure and before washing, the means including a coating roller and other features, as will be hereinafter more fully explained.

15 An object of the invention is to provide means for varying the period of travel of the blueprint paper from one treatment to another so as to allow a chemical solution which has been applied to the paper to remain on the paper a greater or lesser length of time prior to the paper receiving the next treatment so that the chemical shall remain on the blueprint paper the time desired.

Another object of the invention is to provide means for adjusting the blueprint paper so as to raise or lower the blueprint paper relative to the coating roller so as to give the paper a greater or lesser application of the coating and also so as to remove the paper from the coating roller entirely in order to save the coating liquid when it is not necessary to apply the same to the blueprint paper to eliminate waste of the liquid, which is relatively expensive.

Therefore, it has been found important to apply only sufficient of the intensifying solution to perform the intensifying function while at the same time applying sufficient to give the paper a greater or lesser application of the coating and allow the intensifying solution which 40 has been applied to the paper to remain on the paper a greater or lesser length of time prior to receiving the next treatment, such as the rinsing operation. Any intensifying solution remaining on the paper may be entirely rinsed from the surface of the carrier upon the succeeding water rinse. Thus, a further object of the invention resides in the provision of improved mechanism and an improved process employing cooperating elements or steps controlling the 45 amount of intensifying solution applied and the duration of the period during which the intensifying solution remains on the sheet.

The machine illustrated in the drawings, which we have selected as a preferred form for the 50 purpose of illustrating the principle of our inven-

tion, is suited to practice the process of Kwech, Patent No. 1,877,246. This patent can be referred to for the details of practicing the process, which details will not be repeated here, however, as the apparatus is not limited to practicing the process of said patent. 5

Another object has been to provide said means in such a manner as will be inexpensive and easy to assemble and apply as attachments to standard types of blueprinting machines now on the market.

As a result of our invention, in accomplishing the aforesaid objects, we have effected great improvements in respect of means and method for producing highly improved blueprints, and 15 also in respect of effecting great savings of materials and liquids, and in other respects as will be understood by those skilled in the art.

Other objects and advantages will appear more fully hereinafter. 20

The invention will be best understood by reference to the accompanying drawings forming a part of this specification, and in which:

Fig. 1 is an elevation of the feeding end of a blueprint machine with means for adjusting the 25 time of travel of the paper shown applied;

Fig. 2 is a plan view of the left hand portion shown in Fig. 1;

Fig. 3 is a section taken on the line 3—3 of Fig. 2;

Fig. 4 is a detailed view of parts of the above mentioned adjusting means; 30

Fig. 5 is a section taken on the line 5—5 of Fig. 1;

Fig. 6 is a plan view of the removable trough 35 and its rollers; and

Fig. 7 is a sectional elevation of the means for positioning the paper, the paper being shown disengaged.

Referring more particularly to the drawings in which we have shown a form of our invention selected for illustrating the principles thereof, we have shown our invention applied to a conventional blueprinting machine, the feeding end of which is shown in Fig. 1, particularly. 40

Fed to a table 10 is a continuous sheet of blueprint paper 11 which may be brought from a roll conveniently positioned. The paper, with the tracing to be copied, may be led around a semi-cylindrical glass support 12 by an endless belt 13 50 and may be exposed to light from a well known type of arc lamp 14. The belt carries the paper and the tracings after exposure, and the tracings may be dropped on a receiving table 15. The exposed blueprint paper then travels on the end- 55

less belt about a roller 16 suitably mounted on a shaft 17 in a frame 18. The paper and the belt, as clearly shown in Fig. 1, run around an idle roller 19 where the paper and belt separate, 5 the belt returning over the roller indicated at 20 and returning over the glass support back to the roller 16 making a continuous cycle of operation. The belt constitutes the feeding means in a well known manner and may be driven by 10 the shaft 17 from a suitable source of power.

The blueprint paper may then be carried around an idle roller 21 which is adjustably mounted on a pair of sprockets and chains, such as shown, supported in turn on metal angle irons 15 22 in the frame of the machine.

It will be understood that the roller 21 may be adjusted by moving the chain in a suitable manner to position the roller to take up the slack of the blueprint paper and keep the blueprint 20 paper turning properly as will be well known to those skilled in the art. The foregoing are all parts of the conventional blueprint machine and are not claimed as our invention.

In accordance with the principles of our invention we have attached to a well known type 25 of blueprinting machine a pair of supporting frames 23, each of which has a forward vertical leg 24, a central vertical leg 25 and a rear vertical leg 26, one of the frames 23 being clearly 30 shown in Figs. 1 and 3. The frames also have a top rail 27, and an intermediate rail 28 with transverse connecting bars 29 for uniting the supporting frames 23. The frames 23 are supported on the supplemental angle irons 22 as 35 clearly shown in Fig. 1.

The blueprint paper may be led from the idle roller 21 to a positioning roller 30 in a suitable manner mounted on a shaft 31 in bearings 32 secured on the central vertical legs 25. The blueprint paper may then be led over a coating roller 33 for the purpose of supplying an intensifying, or other such solution to the blueprint paper.

The coating roller 33 may be mounted on a 45 shaft 34 having suitable bearings 35, the shaft being mounted on the intermediate rail 28 in the form shown. The shaft 34 may be operated by a driven pulley 36 driven by a belt 37 from a driving pulley 38 mounted on the shaft 17 and 50 the frame 18. The shaft may be provided with conventional collars 39.

The coating roller 33 may be supplied with coating from a semicylindrical trough 40 having ends 41.

55. In the form which we have shown, the trough is provided with means for rendering it easily removable. The trough 40 may have four keepers, 42, as shown, each with a slot 43. Adapted to extend through each slot 43 is a pin 44 on a latch bolt 45. The four latch bolts 45 are adapted to rest in use on the outside of four guide blocks 46, on shelves 47 integrally formed with the lower intermediate rails 28 at the front or receiving end of the frame 23. It will be seen 60 from the foregoing that in normal use when it is desired to place the trough in place the pins may be grasped and moved in the slots toward the ends of the trough, in which case the bolts 45 will be projected on to the shelves outside the 65 guide blocks on the shelves in which event the trough will be securely held in place. When it is desired to remove the trough all that is necessary is to grasp the pins 44 and push them inwardly and the bolts will be withdrawn from 70 the shelves and the trough can be easily removed.

The trough 40 may be provided with a flexible supply pipe 48 connecting with an operating source of supply or fountain 49 supported by a post 50 secured to one of the forward vertical legs 24. The trough 40 will also be provided 5 with a drain pipe 51 having a suitable valve or drain cock 52. The parts just described are clearly shown in Figs. 1, 3, 5 and 6.

After the blueprint paper has been coated by the roller 33 it may be led around an adjustable 10 roller 53 on a shaft 54 with a pair of bearings 55 mounted on a pair of pivoted arms 56 which are pivoted on their other ends on the shaft 31, being provided with collars 57.

A pair of eyelet bolts 58 are pivotally connected to the shaft 54, there being provided suitable collars 59, and the bolts 58 extend through brackets 60 mounted on the inside of the top rails 27 through slots 61 in the brackets 60. The eyelet bolts have threads 62 and are adapted to be 20 adjusted upwardly or downwardly by wing nuts 63, each bolt 58 being provided with a stop lug 64, clearly shown in Figs. 3 and 7 to pass through a slot 61 when the roller carried by the bolt and arm is raised to lift the paper off of or out of 25 contact with the coating roller and rest on the top of the bracket to hold the parts in this position. A timing roller 65 is mounted on shaft 66, in a pair of adjustable sliding blocks 67. The blocks are adapted to slide in slots 68 in inclined brackets 69 mounted on top rails 27.

It will be understood that the shaft 66 turns within the blocks 67 and the blocks which slide in the brackets 69 are provided with collars 70 on the outside of the brackets for maintaining 35 the blocks in the brackets, as clearly shown in Fig. 5. Each block 67 has a T-shaped recess 71 in which is mounted in a swiveling manner, a bolt 72 with threads 73. Each bolt 72 extends through the threaded bore 74 in each bracket 69 40 and each bolt 72 is provided with a handle 75 which moves the corresponding block to a desired position and thereby moves the roller 65 to a desired position. Each inclined bracket 69 is provided along one edge with a scale 76 and each 45 block 67 has a pointer 77 which moves along the scale or calibrations 76 as does the print after passing over the roller 65 to facilitate adjustment.

In the foregoing we have described means 50 whereby the blueprint paper may be lowered or pressed down further, if desired, on the coating roller 33, or it may be lifted up so as to press with relative lightness on the coating roller 33, or if desired, the blueprint paper may be lifted 55 off the coating roller 33 entirely, as illustrated in Fig. 7. By this means the paper can be given as much or as little coating as desired, by increasing or decreasing the surface contact and thus the area contacted or engaged as to the 60 paper with respect to the coating roller 33 and the pressure therebetween. This arrangement is highly advantageous, especially in that if there is no need for coating the blueprint paper the blueprint paper may be lifted off the coating 65 roller 33 and the coating liquid will be saved and not wasted. It will be understood that this adjustment with the position of the blueprint paper in respect to the coating roller 33 may be accomplished simply by adjusting the wing nuts 70 63 on the bolts 58. By corresponding adjustment of the rollers 65, the duration of time in which the treatment, coating or intensifying solution is allowed to remain on the print before being subjected to the next treatment may be 75

properly regulated or kept the same, shortened or lengthened, so that the proper time required will be allowed.

We have also described the means whereby paper can be given a coating by the roller 33 and whereby that coating may be allowed to remain for as little or as long a time relatively as may be required before it is subjected to the next succeeding treatment. For example, it may be desirable to have the coating given by roller 33 remain on the blueprint paper for a longer or shorter time before the paper is subjected to the water treatment, as shown in Fig. 3. These adjustments just described mark a distinct step in the art which will be appreciated by those familiar with the art. It will also be understood that the adjustment just described for controlling the time for leaving the treatment or intensifying coating solution on the blueprint paper may be effected merely by operating the handles 75. If the handles are operated in one direction the roller 65 will be moved upwardly increasing the period of time of travel which the blueprint paper must take before reaching the next treatment. On the other hand if the handles 75 are operated in the opposite direction the roller 65 will be moved downwardly, decreasing the period of time the blueprint paper must travel before reaching the next treatment and thereby decreasing the amount of time in which the coating will be allowed to remain on the blueprint paper before being subjected to the next treatment.

After passing over the roller 65 the paper may be carried around an idle roller 78 superimposed over a drain trough 79 and the blueprint paper may then be carried around another additional roller 80. Pipe 81 extends transversely of the machine with a row of apertures across its entire length and water may be sprayed from this water spray pipe 81 between the rollers 80 and 78, as clearly shown in Fig. 3. Preferably, a sufficient amount of water is sprayed upon the paper or carrier to remove completely the intensifying solution.

The water may be forwarded to the water spray pipe 81 from a suitable source of supply. After being led around the roller 80 the blueprint paper may be led to a positioning roller 82 corresponding to roller 30 suitably mounted on a shaft 82a journaled in bearings similar to bearings 32 but mounted on the rear vertical legs 26, the roller 82 serving substantially the same function as the roller 30. The blueprint paper may then be led over a potash roller 83 or other suitable roller suitably mounted on a shaft 84 suitably mounted on the upper rear intermediate rails 28 and operated by a driven pulley 85 driven by a belt 86 from a driving pulley 87 fixed on the shaft 84. The potash coating roller 83 functions in substantially the same manner as the coating roller 33 to supply the paper with the potash liquid. A trough similar to the trough 40 is provided in conjunction with the potash roller 83 and is provided with similar means of removability. The trough for the roller 83, as is the roller 33, is provided with a source of potash supply 88 carried through a supply tube 48', and the trough has a drain similar to the drain pipe 51.

There is also provided means for pressing the blueprint paper more or less lightly on the roller 83, or lifting the blueprint paper off, as is the case with the roller 33, and the means employed 75 are substantially the same, there being an ad-

justable roller 89 having means of adjustment similar to that of roller 53, excepting that the bolts 80 are slightly shorter than the bolts 53.

Roller 89 is mounted on a shaft having bearings on arms 91, and arms 91 are pivoted on shaft 92 instead of the shaft of the roller 82 corresponding to the roller 30 in a manner similar to the mounting of the arms 56 heretofore described with respect to the shaft 31 and the shaft 54.

The shaft 92 has a pair of bearings 93 mounted on the rear vertical legs 26. The paper may be led around the roller 89 to a discharge roller 94 from which it may be led to the washing and drying sections of the conventional blueprint machine.

In the practical operation of the machine with our invention applied we have found it satisfactory to operate the shaft 84 two times as fast as the shaft 34, or four times as fast as the shaft 17, with the shaft 34 operating two times as fast as the shaft 17. As shown in Fig. 1, shafts 34 and 84 rotate counter-clockwise whereby the peripheral travel of the rollers is opposite that of the paper, but should the speed of the machine be so reduced that this driving action would result in the application of too great an amount of intensifying solution or oxidizing solution, this may be corrected by proper adjustment, such as by twisting or crossing the laps of belt 37 to reverse the drive.

It will be understood by those skilled in the art that blueprint paper or other photo-sensitized carrier is customarily prepared by coating a suitable type of paper with a ferric salt such as ferric ammonium citrate or oxalate, which will be reduced by the action of light to the ferrous state. With the ferric salt is admixed a second compound which combines with the reduced iron compound to form a highly colored image. It is customary to employ potassium ferricyanide.

A diagram, the reproduction of which is desired, may be interposed over the coated paper and then exposed to the action of actinic light for a period of time sufficient to insure reduction of the ferric ammonium citrate.

In accordance with the invention of the Kwech patent above referred to, before being washed with water as was the case before Kwech's invention, the exposed paper is subjected to a bath containing a neutral or alkaline solution of a ferrocyanide reducing agent capable of intensifying the image. While it is preferred to employ potassium ferrocyanide, other compounds such as ammonium ferrocyanide, sodium ferrocyanide and calcium ferrocyanide may also be used. It has been found that considerably more desirable results are obtained when the solution is alkaline, for example, having a pH of 8 or more. Sodium carbonate or other alkaline compound may be employed to impart the desired alkalinity. With the potassium ferrocyanide bath may be combined a stronger reducing agent or inhibitor such as sodium hyposulfite, sodium sulfite, or potassium meta bisulfite. The amount of inhibitor will depend upon the length of time between the intensifying bath and the oxidizing bath to which the paper is later subjected.

Subsequent to the intensifying bath, the paper is subjected to a water bath and an oxidizing bath.

To illustrate, a photosensitive base is prepared by coating paper, cloth or some similar carrier with a 16 percent solution of ferric ammonium citrate, a 16 percent solution of potassium ferrocyanide, and a 5 percent solution of oxalic acid.

The paper prepared in this manner is exposed beneath the desired diagram to light.

After exposure the paper is subjected to an intensifying solution composed of an 18 percent solution of potassium ferrocyanide to which is added 1 percent sodium carbonate and approximately 3 percent sodium sulfite.

The intensified paper is then washed with water, and immersed in a 7 percent solution of potassium dichromate.

Following the oxidizing bath, the paper is again washed with water, and dried.

The above is given as an instance of the use of the apparatus described and it will be understood that the apparatus is not limited however to the use of such a process.

While we have illustrated and described the preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

Having thus described our invention, what we claim as new and desire to secure by Letters Patent is:

1. In a print machine, means for adjusting the travel of the print paper, said means including a positioning roller around which the paper is adapted to be drawn over a coating roller for applying an intensifying solution thereto, a coating roller over which the paper is adapted to be drawn from the positioning roller, said positioning roller being located at one side of and below the coating roller, a second roller at the other side of and above the coating roller around which the paper is adapted to be drawn after it has left the coating roller, an adjustable roller spaced a considerable distance above the aforesaid rollers and over which the paper travels after leaving the second roller adapted to be moved relative the other rollers to vary the time of travel of the coated paper prior to the next succeeding treatment of the paper, said adjustable roller being mounted in a pair of slideable blocks having a pointer, brackets in which said blocks are slidably mounted having an inclined calibrated edge with which the pointer cooperates and along which the paper travels and means for adjusting said blocks and adjustable roller relative said brackets.

2. In a machine of the character described, mechanism for subjecting sensitized material to the action of light, mechanism for applying an intensifying solution to the surface of said material, mechanism for rinsing the surface of said material, and means for regulating the distance of travel of said material between said intensifying solution applying mechanism and said rinsing mechanism.

3. In a machine of the character described, mechanism for subjecting sensitized material to the action of light, mechanism for applying an intensifying solution to the surface of said material faster than the movement of the material when subjected to the action of light, mechanism for subsequently rinsing the surface of said material, means for regulating the distance of travel of said material between said intensifying solution applying mechanism and said rinsing mechanism, and means for applying an oxidizing solution to the surface of said material faster

than the movement of the material when applying the intensifying solution.

4. In a machine of the character described, mechanism for subjecting sensitized material to the action of light, mechanism for applying an intensifying solution to the surface of said material, mechanism for rinsing the surface of said material, and means for regulating the distance of travel of said material between said intensifying solution applying mechanism and said rinsing mechanism, said intensifying solution applying mechanism constructed and arranged to apply a variable amount of solution depending upon the pressure and area of surface contact of said material with the applying mechanism.

5. In a machine of the character described, mechanism for subjecting sensitized material to the action of light, mechanism for applying an intensifying solution to the surface of said material twice as fast as the movement of the material when subjected to the action of light, mechanism for rinsing the surface of said material, means for regulating the distance of travel of said material between said intensifying solution applying mechanism and said rinsing mechanism, and means for applying an oxidizing solution to the surface of said material twice as fast as the movement of the material when applying the intensifying solution, said intensifying solution applying mechanism constructed and arranged to apply a predetermined amount of solution depending upon the pressure and/or surface contact of said last named mechanism with said material.

6. In a machine of the character described, mechanism for subjecting sensitized material to the action of light, mechanism for applying an intensifying solution to the surface of said material, mechanism for rinsing the surface of said material, means for regulating the distance of travel of said material between said intensifying solution applying mechanism and said rinsing mechanism, said intensifying solution applying mechanism constructed and arranged to apply a predetermined amount of solution depending upon the period of travel, area and surface contact of said material, and means auxiliary to the mechanism for applying an intensifying solution for controlling the effective amount of surface and pressure of said material subjected to said intensifying solution applying mechanism during the application thereof and pressure against same.

7. In a machine of the character described, mechanism for applying an intensifying solution to the surface of a sheet of traveling material, mechanism for rinsing the surface of said material, said intensifying solution applying mechanism constructed and arranged to apply a predetermined amount of said solution whereby said solution will remain on the sheet for a greater or lesser length of time prior to reaching said rinsing mechanism, and means for regulating the distance and time of travel of said material between said solution applying mechanism and said rinsing mechanism.

8. The process herein described comprising subjecting a traveling sheet of sensitized material to the action of light, applying a predetermined amount of intensifying solution to the surface of said material, rinsing the surface of said material, and regulating the period and distance of travel of said material between said intensifying solution applying operation and said rinsing operation whereby said intensifying so-

lution will remain on the paper a greater or lesser length of time prior to reaching said rinsing operation.

9. The process herein described comprising subjecting a traveling sheet of sensitized material to the action of light, applying a predetermined amount of intensifying solution to the surface of said material while said material is in a dry state, subsequently rinsing the surface of said material, regulating the period and distance of travel of said material between said intensifying solution applying operation and said rinsing operation whereby said intensifying solution will remain on the paper a greater or lesser length of time prior to reaching said rinsing operation, and thereafter applying an oxidizing solution to the surface of said material.

10. In a print machine, means for making a print of a tracing, said means including mechanism for exposing the print to the action of light modified by a design, mechanism for applying an intensifying solution to the print after said exposure, said means including a coating roller, and means for adjusting the travel of the print during and subsequent to applying said solution and prior to rinsing or other treatment, said means including rollers around which the paper is drawn, and mechanism for varying the relative positions and spacing of said rollers to increase or decrease the period of travel of the print, including an adjustable roller, a bracket in which said roller is slidable and means to slide said roller and hold the same in adjusted position.

11. In a print machine, means for making a print of a tracing, said means including mechanism for exposing the print to the action of light modified by a design, mechanism for applying an intensifying solution to the print after said exposure, said means including a coating roller, means for rinsing said print, means for applying an oxidizing solution to the print after rinsing, and means for adjusting the travel of the print after coating and before rinsing, said means including rollers around which the paper is drawn, and mechanism for varying the relation of said rollers to increase or decrease the period of travel of the print, including an adjustable roller, an inclined bracket mounted in fixed position and having an inclined edge, the print traveling along said edge, a slidable bearing carried by the bracket and supporting the roller and means for adjusting the bearing and roller toward and away from the aforesaid rollers and holding the same in adjusted position.

12. In a print machine, means for making a print of a tracing, said means including mechanism for exposing the print to the action of light modified by a design, mechanism for applying an intensifying solution to the print after said exposure, said means including a coating roller, means for subsequently treating the print, and means for adjusting the travel of the print prior to said subsequent treatment, said means including rollers around which the paper is drawn, and mechanism for varying the relation of said rollers to increase or decrease the period of travel of the print, including an adjustable roller, brackets mounted in fixed position, slidable bearings carried by the brackets and supporting the roller, at least one of said bearings having a pointer and a scale on at least one of the brackets along which the print travels and with which the pointer cooperates.

13. In a blueprint apparatus a frame, brackets on the frame, a roller supported for adjustment

longitudinally of the brackets, means for exposing the print to the action of light modified by a design, a plurality of coating rollers, troughs for each of said rollers, positioning rollers around which the print is caused to travel to engage the coating rollers, pivot arms and rollers carried by said arms and adjustable therewith to vary the area of contact by the paper with the coating rollers and the pressure therebetween.

14. In a blueprint apparatus a frame, brackets on the frame, a roller adjustably supported to be raised or lowered longitudinally of the brackets, means for exposing the print to the action of light modified by a design, a plurality of coating rollers, troughs for each of said rollers, means for maintaining the level of the coating liquid in said troughs and into which the rollers dip, positioning rollers around which the print travels in conjunction with the aforesaid rollers and positioned on one side of the coating rollers, and swingably supported rollers on the other sides of the coating rollers and above the same beneath which the print travels, said swingably supported rollers being adapted to be held in adjusted relation to the coating rollers to vary the area of contact and pressure with the coating rollers by the print or to be held out of contact therewith.

15. In a blueprint apparatus a frame, brackets on the frame, a roller adjustably supported longitudinally of the brackets, means for exposing the print to the action of light modified by a design, a plurality of coating rollers, troughs for each of said rollers, means for maintaining the level of the coating liquid in said troughs and into which the rollers dip at a fixed point, positioning rollers around which the print travels in conjunction with the aforesaid rollers and positioned on one side of the coating rollers, arms pivotally mounted, rollers carried by the arms, adjustable connections between the arms and the frame to move the print passing between the positioning rollers and the rollers carried by the arms into or out of contact with the coating rollers and to vary the surface contact therewith, said print passing over the adjustable roller whereby adjustment of the latter will vary the time between the periods of contact of the print with a coating roller and subsequent treatment thereof, and a discharge roller at the end of one arm.

16. In a print machine, means for adjusting the position of the print paper relative to a coating roller, said means including a positioning roller around which the paper is adapted to be drawn, said positioning roller being fixedly located on one side of the coating roller and an adjustable roller movably supported and positioned on the other side of the coating roller around which the paper is adapted to be drawn after it leaves the coating roller, said adjustable roller being adapted to be lowered or raised relative to the coating roller to vary the degree of pressure and area of contact between the paper and the coating roller, another adjustable roller over which the paper is trained after passing around the aforesaid adjustable roller and means for rinsing the paper, said second mentioned adjustable roller serving to vary the distance and time of travel of the paper between the coating and the rinsing operations.

17. In a machine of the character described, mechanism for subjecting sensitized material to the action of light, mechanism for applying an

intensifying solution to the surface of said material, mechanism for rinsing the surface of said material, means for regulating the distance of travel of said material between said intensifying solution applying mechanism and said rinsing mechanism and means for regulating the

area of contact and increasing or decreasing the pressure between the material and the intensifying solution applying mechanism.

FREDERICK H. CROFOOT. 6
EDWARD G. CROFOOT.
